US00D770514S

(12) **United States Design Patent** (10) **Patent No.:** **US D770,514 S**
Bae et al. (45) **Date of Patent:** ** *Nov. 1, 2016

(54) **DISPLAY SCREEN PORTION WITH GRAPHICAL USER INTERFACE**

(71) Applicant: **Samsung Electronics Co., Ltd.**, Suwon-si (KR)

(72) Inventors: **Hyo-Jin Bae**, Seoul (KR); **Yong-Chae Jung**, Seoul (KR); **Min-Hae Kim**, Seoul (KR)

(73) Assignee: **Samsung Electronics Co., Ltd.**, Suwon-si (KR)

(*) Notice: This patent is subject to a terminal disclaimer.

(**) Term: **15 Years**

(21) Appl. No.: **29/531,376**

(22) Filed: **Jun. 25, 2015**

Related U.S. Application Data

(63) Continuation of application No. 29/457,125, filed on Jun. 7, 2013, now Pat. No. Des. 737,837.

(30) **Foreign Application Priority Data**

Feb. 23, 2013 (KR) 30-2013-0009592

(51) **LOC (10) Cl.** **14-04**

(52) **U.S. Cl.**

USPC **D14/487**

(57) **CLAIM**

We claim the ornamental design for a display screen portion with graphical user interface, as shown and described.

DESCRIPTION

The sole FIGURE is a front view of a display screen portion with graphical user interface showing our new design. The broken line showing is included for the purpose of illustrating portions of the article and forms no part of the claimed design.

1 Claim, 1 Drawing Sheet
